UNITED STATES PATENT OFFICE.

JOSEPH E. HASKELL, OF CHICAGO, ILLINOIS.

PORTABLE TELESCOPIC CASE.

SPECIFICATION forming part of Letters Patent No. 281,268, dated July 17, 1883.

Application filed May 23, 1883. (No model.)

To all whom it may concern:

Be it known that I, JOSEPH E. HASKELL, of Chicago, in the county of Cook and State of Illinois, have invented certain new and useful

5 Improvements in Portable Telescopic Cases, of which the following, in connection with the accompanying drawings, is a specification.

In the drawings, Figure 1 is a perspective view of a portable telescopic case embodying 10 my invention. Fig. 2 is a vertical central section of a part of the same in the plane of the line $x x$. Fig. 3 is a detail in perspective of the spring-catch. Fig. 4 is a section in the plane of the line $y y$, showing the catch in its 15 closed position for locking the case. Fig. 5 is a like representation, showing the catch open; and Fig. 6 is a like representation, showing the catch closed and locked.

Like letters of reference indicate like parts. 20 My invention relates to that class of telescopic cases which are portable and adapted to be carried by hand, and in which the top part or cover slides telescopically upon the body of the case in opening and closing the 25 same.

Heretofore the top part or cover has been retained upon the body by means of straps and buckles, and also by means of metallic fastenings applied to the ends of the case.

30 My invention has for its object the improvement and the construction and operation of the class of fastenings last above referred to; and it consists in the means which I employ for that purpose.

35 A represents the body of the case.

B is a metallic plate serrated on its outer face, and applied vertically to the central parts of the ends of the case. The vertical edges of the plate B project laterally, as shown at $a a$.

40 C is a plate applied to the end of the top part or cover, D.

E is a spring attached at its lower end to the lower parts of the plate C. The upper end of this plate is adapted and arranged 45 to engage the serrations or notches $a' a'$ on the plate B, and when so engaged the top or cover D is temporarily prevented from being raised, but may be moved down with facility as far as the body A or its contents will permit.

50 F is a pin or catch swiveled in the upper or

free end of the spring E, and b is an oblong opening or slot in the plate C. The spindle or cylindrical part of the catch F passes through and turns in the slot b.

c c are shoulders projecting laterally from the forward part of the pin F. When the shoulders $c c$ lie horizontally, they lap the face of the plate C, and are so located that they will then hold the spring E out of engagement with the notches $a' a'$, at which time the lid D may 55 be moved up and down or removed without hindrance. The shoulders $c c$, however, when arranged vertically, will pass through the slot b, being drawn through it by the action of the spring E, which is then free to move in and 60 engage the notches $a' a'$, so as to temporarily 65 lock the cover D down.

d is a ring turning in the outer end of the pin F, and whereby the position of that pin may be controlled or varied with facility for 70 the purpose of locking and releasing the lid D.

It may be of advantage on many accounts to lock the spring E in engagement with the notches $a' a'$, and for that purpose I apply a small lock, G, to the inner face of the plate C, 75 and pierce or mortise the pin F to receive the lock-bolt e, as represented in Fig. 6.

H is the key.

I are bent or angular plates applied to the plate C, and extending back of the projections 80 $a a$, thus serving as guides for the lid or cover D.

It will be perceived from the foregoing description and from reference to the drawings that the lid D may be removed and replaced with facility, and easily fastened and securely 85 held in its closed position by means of the engagement of the spring E with the notches $a' a'$, and that the lock G may be readily combined therewith, if deemed desirable. The fastening devices now described may be applied either to one or to both ends of the case, 90 preferably to both ends.

Having thus described my invention, what I claim as new, and desire to secure by Letters Patent, is—

1. The combination, in a portable telescopic case, of the body A, provided with the notched or serrated plate B, and the top or cover D, provided with the spring E, adapted and arranged to engage the said serrations, and a 95 100

catch applied to the said spring and accessible from the outside of the case, substantially as and for the purposes specified.

2. The combination, in a portable telescopic case, of the serrated plate B, and the spring-catch E, provided with the rotary shouldered pin F, passing through a slot in the case, substantially as and for the purposes specified.

3. The combination of the catch E, pierced to pin F, a lock having its bolt arranged to enter the opening in the said pin, the serrated plate

B, the body A, and top D, substantially as and for the purposes specified.

4. The combination of the serrated plate B, having thereon the extensions *a a*, the plate C, provided with the bent or angular plates I I, the spring E, and the pin F, substantially as and for the purposes set forth.

JOSEPH E. HASKELL.
